UNITED STATES PATENT OFFICE.

GIOVANNI LUIGI BUTTA, OF CONCORD, NEW SOUTH WALES, AUSTRALIA.

JACK.

Application filed January 15, 1925. Serial No. 2,667.

To all whom it may concern:

Be it known that GIOVANNI LUIGI BUTTA, subject of Great Britain, residing at El Retiro, Correy Avenue, Concord, in the

5 State of New South Wales, Commonwealth of Australia, has invented certain new and useful Improvements in Jacks, of which the following is a specification.

The invention relates to lifting and lowering jacks of the class comprising telescoping screws provided with ratchet devices adjacent the points where one screw enters another, such devices being oppositely disposed and reversible so that the jack may 10 be raised or lowered with a double action whereby loss of motion in manipulating the jack is avoided.

The present invention has for its object to provide an improved jack of this class in 20 which the construction is simplified and which has the added advantage that it can be largely manufactured from standard commercial material. The invention also makes it possible to make all the screws of 25 the same thread, either all right-handed or all left handed.

The invention comprises a screw threaded standard in which is slidably mounted a screw threaded member, a single casing surrounding the junction of such standard and member and carrying reversible pawls which respectively engage ratchet teeth on 30 nuts on said standard and member.

Referring now to the accompanying 35 drawings which illustrate by way of example one convenient embodiment of the invention:—

Figure 1 is a central vertical section of the improved jack in extended position with 40 certain parts omitted or broken away.

Figure 2 is a central vertical section on a large scale showing the jack in collapsed position.

Figure 3 is a detail vertical section on a 45 large scale, and

Figure 4 is a detail perspective view.

The jack may be provided with any suitable base, that shown in the drawing being a plate 10 of large diameter having a 50 central boss 11 and being axially bored and internally screw threaded at 12 to receive the screw threaded lower end of the standard 13. The standard 13 is of any suitable length and externally screw threaded 55 from the top downwardly throughout the major portion of its length; slidably within

the standard 13 is an externally screw threaded tube 14 of greater length than the standard and slidably within the tube 14 is a screw threaded rod 15 upon which is a 60 nut 16 and a bearing block 17 integral with or secured to its upper end by means of the screw 18. Screwed on to the standard 13 is a nut 19, another nut 20 being screwed on to the tube 14; and interposed between 65 these two nuts and surrounding the standard 13 is a tubular distance piece or slidable sleeve 21 that is provided with a centrally situated annular channel 22. Surrounding the nuts 19 and 20 and the slidable sleeve 70 21 is an outer casing 23 that is centrally bored and tapped to receive a screw 24, the end of which passes through the casing 23 and lies slidably within the annular channel 22 in the slidable sleeve 21. The outer 75 casing is also provided with upper and lower tubular bosses 25 and 26 that form housings for their respective spring operated reversible pawls 27 and 28. Centrally upon the outer casing is a lug 29 that lies 80 in the slotted end 30 of the telescopic lever 31 and whereby the latter may be pivotally secured at 32. The lever 31 is axially bored throughout a portion of its length from the outer end thereof to slidably receive a rod 85 33 that has formed or secured to its outer end an internally threaded cap 34 adapted to be screwed on to the outer end of the lever 31. The lower end of the casing is closed 90 by a washer-like plate 35 that surrounds the standard 13 and is secured to the end of the casing 23 by means of the screws 36. The upper end of the casing is also closed 95 by a washer-like plate 37 that surrounds the tube 14 and is secured to the upper end of the casing by means of the screws 38. The nut 16 is seated upon the plate 37 or adjacent thereto when the appliance is in its collapsed position while the nut 20 lies immediately below that plate and within the 100 casing 23. Each of the nuts 19 and 20 are provided with ratchet teeth 39 cut upon their external peripheral face, the respective housings 26 and 25 being positioned so that the spring operated pawl carried 105 thereby will engage with their respective ratchet teeth.

The bosses 25 and 26 are each externally screw threaded to receive a specially constructed internally screw threaded cap 40. 110 Each pawl 27 and 28 is secured to one end of or is integral with a rod or stem 41 that

passes slidably through a hole bored axially in the top of the cap 40, the other end of the stem 41 being provided with milled head or nut 42 by means of which the pawls may 5 be manually adjusted. The cap 40 is diametrically slotted at 43 in order that the pin 44, that passes through and is rigidly secured to the stem 41, may normally lie therein in order to maintain the pawl in its 10 proper position. The depth of the slot 43 will be such that when the milled head 42 with its stem 41 and pawl 28 (or 27) is pulled outwardly and given a quarter turn the pin 44 will lie upon the outer extremity 15 of the cap 40 transversely across the slot 43 and the pawl 28 (or 27) be thereby held clear of the ratchet teeth 39 (see pawl 27) in Figure 2. A helical spring 45 surrounds the stem 41 and is normally held in 20 partial compression between a shoulder formed by the pawl and the under face of the top of the cap 40. Both the pawls 27 and 28 have a square engaging face and an opposite bevelled or rounded face so that 25 alternately they will engage their respective ratchet teeth 39 when the outer casing is turned in one direction and will move radially outward and pass over those ratchet teeth 39 when the casing is turned 30 in the opposite direction.

In operating the appliance the ratchet teeth will be set oppositely so that they will engage their respective ratchets 39 alternately as the lever 31 is operated to rock 35 the casing first in one direction and then the other.

In order to limit the upward travel of the sleeve 21 and prevent it rotating upon the standard 13 a longitudinal slot 46 is 40 cut through the thread on the standard, the sleeve 21 being provided with an internal radial stop 47 adapted to slide in the slot 46. In register with the slot 46 and at a suitable distance from the top of the standard 13 a slotted hole 48 is cut to receive a pin 49 shaped and dimensioned to enable it to project inwardly so that its inner end lies slidably in a longitudinal slot 50 cut through the thread upon the tube 55 14, the outer end of such pin lying flush or thereabout, with the thread on the standard 13. In order to limit the downward movement of the parts upon the standard 13 a screw 51, (Figures 2 and 3) may be inserted in the slot 46 and adapted to form a stop for the nut 19, the screw 51 being preferably at a point low enough to prevent the top of the sleeve 21 descending below the pin 49. Upward movement 60 of the parts is arrested when the stop 47 abuts against the outer end of pin 49. Upward movement may if desired be stopped by another screw (not shown in the drawings) which may be inserted in the tube 65 14 near the bottom of the slot 50 so that

as the tube 14 is raised to its full extent by the rotation of the nut 20 the screw will abut against the underside of the inner end of the pin 49 and prevent any further upward movement of the tube. The rod 70 15 will be provided with a longitudinal slot 52 and stop 53 at the bottom thereof whereby its upward movement may be limited by a screw 54 inserted in and near the top of the slot 50 in the tube 14. 75

In cases where an appliance is not required for comparatively high lifts the rod 15 may be dispensed with and a bearing block 17 secured in any suitable manner to the upper end of the tube 14. 80

In operating the appliance for high lifts the rod 15 may be slid out of the tube a suitable distance and the nut 16 screwed down until it abuts against the top of the tube 14. The pawls 27 and 28 will now be adjusted and the lever 31 raised to a position radial to the casing 23 and moving it back and forth in a horizontal plane until the desired height is reached. When lowering again the pawls will be reversed by pulling the upper and lower heads 42 outwardly and giving them a half turn and then releasing them so as to allow the pins 44 to resume their position within the slots 43. By again operating the lever 31 the tube 14 will be drawn downwardly into the standard 13 while the casing 23 and its attachments will be drawn downwardly upon the standard. 95

It will be apparent that, when the pin 41 of each pawl is resting on the outer extremity of the cap 40, the pawls are held clear of the ratchet teeth, and thus the jack may be locked in any desired position. 100

What I claim is:

1. A jack comprising a base secured to an externally screw threaded tubular standard, an externally screw threaded member slidably within said standard, externally toothed nuts on said standard and member, means for preventing rotation of said member, means for maintaining said toothed nuts at a constant distance apart, reversely disposed pawls for engaging the teeth on said nuts, a structure carrying both of the pawls and means for oscillating said structure about the axis of the standard. 110

2. A jack as defined in claim 1 having an externally screw threaded rod slidably mounted in said member, said rod having a nut thereon and a bearing block secured thereto. 120

3. A jack comprising a base secured to an externally screw threaded tubular standard, an externally screw threaded member slidably within said standard, externally toothed nuts on said standard and member, a tubular distance piece or sleeve between said nuts and surrounding said standard, a longitudinal slot in said member, a pin on the 125 130

- standard adapted to slide in said slot, an external longitudinal slot in said standard, an internal stop on the sleeve and adapted to slide in the slot in the standard whereby 5 said externally screw threaded member and distance piece are prevented from rotating, a structure carrying the pawls and distance piece and means to oscillate said structure about the axis of the standard.
- 10 4. A jack as defined in claim 1 in which each reversible and disengageable pawl is slidably housed in a hollow boss formation secured to or integral with the casing and is provided with a stem that projects 15 through a cap adapted to be screwed on to the boss, a transverse slot in the cap, a transverse pin rigidly secured to the stem and adapted normally to lie in the slot in the cap, a spring surrounding the stem and normally 20 held in partial compression between the pawl and the inner face of the cap, a head or nut on the outer extremity of the stem whereby the pawl may, when required, be pulled clear of the ratchet and turned so 25 that the pin may lie transversely across the slot and the pawl be thereby temporarily held disengaged from the ratchet.
5. A jack as defined in claim 1 having a block integral with or secured to a screw 30 threaded rod, a nut on said rod adapted to be seated upon the upper end of the oscil-
- latory structure for the purpose of adjusting the operative height of the jack, means for preventing the rod from rotating within the externally screw threaded member and means for limiting the upward movement of the said rod. 35
6. A jack as defined in claim 1 in which the oscillatory structure consists of a tubular casing enclosing the externally-toothed nuts and the distance piece or sleeve and adapted to move longitudinally therewith, and plates for closing the ends of said casing and wherein the oscillating means comprises a lever preferably pivotally connected to the casing whereby the latter may be rotated in opposite directions to cause the pawls alternately to engage the teeth on said nuts and rotate the said nuts in opposite directions. 40
7. A jack as defined in claim 3 wherein the pawl-carrying structure consists of a tubular casing and the means for oscillating said casing consists of a pivotally connected telescopic lever. 45
- 50 In testimony whereof I affix my signature in presence of two witnesses.
